UNITED STATES PATENT OFFICE

1,931,560

MINING MACHINE

Leon E. Simmons, Claremont, N. H., assignor
to Sullivan Machinery Company, a corpora-
tion of Massachusetts

Application May 12, 1932. Serial No. 610,888

17 Claims. (Cl. 262—30)

This invention relates to mining machines, and more particularly to improvements in cutter bars of such machines.

An object of this invention is to provide an improved mining machine cutter bar. Another object is to provide an improved cutter bar of more rugged construction and less expensive to manufacture than heretofore. Still another object is to provide a cutter bar of an improved construction whereby, while retaining all the advantages of cutter bars of previous design, a comparatively simple and less expensive construction is obtained. A still further object is to provide improved means for attaching the mining machine cutter bar to the body of the machine. These and other objects of this invention will, however, hereinafter more fully appear in the course of the following description, and as more particularly pointed out in the appended claims.

20 In the accompanying drawing, there is shown for purposes of illustration, one form which the invention may assume in practice.

In this drawing,—

Fig. 1 is a longitudinal vertical sectional view taken through a coal mining machine having embodied therein the illustration embodiment of the cutter bar construction, parts being shown in elevation to facilitate illustration.

Fig. 2 is a plan view of the improved cutter bar, a portion of the cutter bar support being shown in horizontal section.

Fig. 3 is a transverse vertical sectional view taken substantially on line 3—3 of Fig. 1.

In this illustrative embodiment of the invention the improved cutter bar construction is embodied in a coal mining machine generally designated 4, of a standard construction, herein of the flexibly fed, continuous cutter type, although it is evident that the improved cutter bar structure may be embodied in mining machines of various other types. In this instance the mining machine 4 is of the same general design as that disclosed in a copending application of one Morris P. Holmes, Ser. No. 367,895, filed June 3, 1929, now matured in Patent No. 1,875,836, granted Sept. 6, 1932, and comprises a body 5 having a plane bottom surface 6 adapted to rest upon and slide in any direction over the mine floor. Secured within the machine body and projecting forwardly lengthwise of the machine is the improved cutter bar 7 having an improved supporting structure, generally designated 8, whereby the cutter bar is adjustably secured within the machine body in an improved manner. Arranged within the machine body and located

above the cutter bar is a horizontal motor 9 herein having its power shaft 10 extending longitudinally of the machine. Fixed to the rearward end of the motor power shaft is a bevel pinion 11 meshing with a bevel gear 12 keyed to a vertical shaft 13 suitably journaled within the machine body. Rotatable with and driven by the shaft 13 is a spur pinion 14 meshing with a large spur gear 15 connectible by a clutch 16, of the well-known sliding pin type, to a cutter chain driving sprocket 17. The sprocket 17 is arranged within the rear end of the machine body, and this sprocket engages and drives an endless cutter bit carrying cutter chain 18 mounted on the margin of the cutter bar for circulation therabout. The machine is fed and guided through haulage drums and cooperating draft cables in the manner clearly described in the above mentioned Holmes patent.

Now referring to the improved cutter bar structure, it will be noted that formed on the bottom of the motor casing at 19 is a longitudinal slot or groove, while formed on the upper surface of the detachable bottom plate 20 of the machine body is a similar slot or groove 21, these grooves being arranged at the longitudinal vertical center of the machine and extending rearwardly in the manner shown in Fig. 1. Seated within these slots and held in position by bolts 22, which also are utilized to attach the bottom plate 20 in position, is a guiding and positioning block 23. The cutter bar 7 comprises top and bottom plates 24 and 25 arranged in vertical spaced relation by means of spacing blocks or bar elements 26, 26, the plates 24, 25 and blocks 26 being rigidly secured together as by rivets 27. The inner surfaces of the plates 24, 25 are provided with grooves 28, 28 extending about the bar, and which cooperate to form a guideway or channel for the cutter chain 18, as is well understood by those skilled in the art. In this improved construction the top and bottom plates are longitudinally slotted at 29, 29 for receiving the block 23, the slots each having closed ends, i. e. opening at neither end through an extremity of the plate in which they are formed. The block 23 is provided with lateral ledges 30, 30 extending along its length and the ledges project within grooves 31, 31, formed by the plates 24, 25 and spacing blocks 26, thereby cooperating to support the cutter bar.

Means is afforded for adjusting the cutter bar longitudinally relative to the block 23 to effect adjustment of the tension of the cutter chain, and this adjusting means comprises an adjust-

ing screw 32 housed within the cutter bar and threadedly connected at 33 within a projection 34 formed integral with the block 23, as shown in Fig. 1. This adjusting screw is journaled 5 within a bearing member 35 attached to the cutter bar, and is provided with a head 36 provided with openings 37 for the reception of a suitable turning instrument, the top plate 24 of the cutter bar being slotted at 38 to permit insertion of the 10 turning instrument within the openings 37. It will thus be seen that upon rotation of the adjusting screw, the latter is threaded inwardly and outwardly relative to the threaded projection 34, thereby to move the cutter bar longitudinally 15 either inwardly or outwardly relative to the block 23. When it is desired to remove the cutter bar from the machine body, the machine is turned on its side, and the screws 22 removed, thereby permitting longitudinal withdrawal of 20 the cutter bar and block 23 from the machine body, the block 23 sliding outwardly along the slots 19, 21 during withdrawal of the cutter bar.

From the foregoing description, it is clearly 25 evident that an improved cutter bar is provided, of an exceedingly simple and rugged construction, the main body of the bar consisting only of the top and bottom plates and cooperating spacing members held in position by the guiding and positioning block 23. Further, by the provision 30 of the improved bar supporting and positioning means, it is possible to provide a cutter bar of simple and rugged construction and with a relatively small amount of machining of the parts, the cutter bar being held in position by 35 the guide block, and the latter constituting the sole element for supporting and positioning the bar within the machine body. These and other advantages of the improved cutter bar structure will be clearly apparent to those skilled in the 40 art.

While there is in this application specifically described one form which the invention may assume in practice, it will be understood that this form of the same is shown for purposes of 45 illustration and that the invention may be modified and embodied in various other forms without departing from its spirit or the scope of the appended claims.

What I claim as new and desire to secure by 50 Letters Patent is:

1. A mining machine cutter bar including top and bottom plates having longitudinal slots therein and bar supporting means including a support having parallel frame portions and a guiding and 55 positioning block arranged within said slots and interposed between and rigidly secured to said frame portions, said guiding and positioning block being releasable from said frame portions for withdrawal with said bar longitudinally from between said portions while the latter retain their normal space relation.

2. A mining machine cutter bar including top and bottom plates having longitudinal slots therein and bar supporting means including a support having parallel frame portions and a guiding and positioning block arranged within said slots and interposed between and rigidly secured to said frame portions, said guiding and positioning block being releasable from said frame portions for withdrawal with said bar longitudinally from between said portions while the latter retain their normal space relation, and means arranged between said cutter bar and said block for longitudinally adjusting the cutter bar.

3. A mining machine cutter bar including top

and bottom plates arranged in spaced relation, spacing members arranged between said plates, said plates having longitudinal slots therein, and bar supporting means including a support having parallel frame portions and a supporting and 80 positioning block arranged within said slots and interposed between and rigidly secured to said frame portions, said block having lateral ledges cooperating with said spacing members and plates.

4. A mining machine cutter bar including top and bottom plates arranged in spaced relation, spacing members arranged between said plates, said plates having longitudinal slots therein, bar supporting means including a support having 90 parallel frame portions and a supporting and positioning block arranged within said slots and interposed between and rigidly secured to said frame portions, said block having lateral ledges cooperating with said spacing members and 95 plates, and means arranged between said block and bar for adjusting said bar in a longitudinal direction relative to said block.

5. In a mining machine, a machine body, spaced 100 portions of the body having formed therein longitudinally extending grooves, a guiding and positioning block seated in said grooves and rigidly secured to the body, and a cutter bar having formed therein a longitudinal slot for receiving said guide block.

6. In a mining machine, a machine body, spaced 105 portions of the body having formed therein longitudinally extending grooves, a guiding and positioning block seated in said grooves and rigidly secured to the body, a cutter bar having formed 110 therein a longitudinal slot for receiving said guide block, and means between the cutter bar and guide block for adjusting the bar in a longitudinal direction relative to the machine body.

7. A mining machine cutter bar including top 115 and bottom plates having openings therein and bar supporting means including a support having parallel frame portions and a guiding and positioning member arranged within said openings and interposed between and rigidly secured 120 to said frame portions, said guiding and positioning member being releasable from said frame portions for withdrawal with said bar longitudinally from between said portions while the latter retain their normal space relation.

8. A mining machine cutter bar having a longitudinal slot between its ends, said slot having both its ends closed, and bar supporting means comprising a support and a bar positioning and guiding block attached to said support and extending vertically through said slot.

9. A mining machine cutter bar having a longitudinal slot between its ends, said slot having both its ends closed, bar supporting means comprising a support and a bar positioning and guiding block attached to said support and extending vertically through said slot, and means arranged between said block and bar for adjusting said bar longitudinally relative to said support, said bar sliding longitudinally along said block during such adjustment.

10. A mining machine cutter bar having a longitudinal slot between its ends, said slot having both its ends closed, bar supporting means comprising a support and a bar positioning and guiding block attached to said support and extending vertically through said slot, and means arranged between said block and bar for adjusting said bar longitudinally relative to said support, said block having guides fitting in guideways on said bar

and said bar sliding along said block guides during such adjustment.

11. A mining machine cutter bar having a longitudinal slot between its ends, said slot having both its ends closed, and bar supporting means comprising a support and a bar positioning and guiding block attached to said support and extending vertically through said slot, said block having a series of transverse openings and screws extending through said openings and attached to said support for rigidly securing said block to said support.

12. A mining machine cutter bar having a longitudinal slot between its ends, said slot having both its ends closed, and bar supporting means comprising a support and a bar positioning and guiding block attached to said support and extending vertically through said slot, said block having a series of transverse openings and screws extending through said openings and attached to said support for rigidly securing said block to said support, said support having formed therein a longitudinal groove and a projection extending longitudinally of said block and fitting said groove.

13. A mining machine cutter bar having a longitudinal slot between its ends, said slot having both its ends closed, and bar supporting means comprising a support and a bar positioning and guiding block attached to said support and extending vertically through said slot, said block having a series of transverse openings and screws extending through said openings and attached to said support for rigidly securing said block to said support, said support having formed therein a longitudinal groove and a projection extending longitudinally of said block and fitting said groove, said block slideable longitudinally relative to said support upon withdrawal of the block from said support.

14. A mining machine cutter bar having a longitudinal slot between its ends, said slot having both its ends closed, and bar supporting means comprising a support and a bar positioning and

guiding block attached to said support and extending vertically through said slot, said support having spaced frame portions between which said block is interposed, said frame portions having longitudinal grooves and said block having projections extending longitudinally thereof and fitting said grooves.

15. A mining machine cutter bar having a longitudinal slot between its ends, said slot having both its ends closed, and bar supporting means comprising a support and a bar positioning and guiding block attached to said support and extending vertically through said slot, said support having spaced frame portions between which said block is interposed, said frame portions having longitudinal grooves and said block having projections extending longitudinally thereof and fitting said grooves, said guide block slideable longitudinally relative to the support upon withdrawal of said block from said support.

16. A mining machine cutter bar comprising spaced upper and lower plates, each having a longitudinal slot between its ends, the slot in the upper plate extending co-extensively with the slot in the lower plate and each of said slots having closed ends, and bar supporting means comprising a support having spaced frame portions and a guiding and positioning block interposed between and rigidly attached to said frame portions and extending through said slots.

17. A mining machine cutter bar comprising spaced upper and lower plates, each having a longitudinal slot between its ends, the slot in the upper plate extending co-extensively with the slot in the lower plate and each of said slots having closed ends, bar supporting means comprising a support having spaced frame portions and a guiding and positioning block interposed between and rigidly attached to said frame portions and extending through said slots, and means for adjusting said bar relative to said block, said slots being elongated to permit such adjustment.
